TELEPHONE ATTACHMENT

Filed May 7, 1928

UNITED STATES PATENT OFFICE

DARIO RAPPAPORT, OF NEW YORK, N. Y., ASSIGNOR, BY MESNE ASSIGNMENTS, TO
TRANSAMERICA PRODUCTS CO., INC.

TELEPHONE ATTACHMENT

Application filed May 7, 1928. Serial No. 275,847.

This invention relates to contrivances attachable to instruments used for entry of telephone numbers and other memoranda.

The hitherto used means of this character are in form of pendants to hang freely from the mouthpiece of the instrument and each consists of a card board back to which are attached by loose leaf fasteners a number of alphabetical index cards with intermediate 5 cards for entering names and telephone numbers of different parties. Such pendants have been objectionable, first, because of the inconvenience to handle them while the instrument is in use, then because they easily slip 10 off the instrument and also because they are suitable only for instruments of American 15 type, but not for those of the French type.

The object of this invention is to provide a device which can be readily attached to 20 any type of telephone, that will be convenient to handle when the instrument is in use and can be concealed when not in use.

It also has for its object to provide simple 25 means for the removable attachment of the device to the instrument without changing the construction of the latter.

With these and other objects in view my 30 invention consists in the novel combination, construction and arrangement of parts as will be hereinafter described and defined in the appended claims.

In the accompanying drawings in which 35 similar reference characters denote corresponding parts, Fig. 1 is a perspective view of the base portion of a telephone instrument and of my new contrivance attached hereto; Fig. 2 is a section on line 2-2 of Fig. 3 of the contrivance; Fig. 3 is a vertical section thereof and Figs. 4 and 5 are respectively a sectional top plan and elevation of a modified 40 form of construction.

B denotes the circular base of an ordinary telephone instrument. My device comprises a substantially box-shaped support 10 open 45 on top and at its front and provided with three or more somewhat resilient arms 11 which extend from the sides of the walls of said box shaped support at suitably spaced intervals and are bent at their free ends to 50 form clamps 11^a adapted to snap around the

circumferential edge of said base B, and thereby hold said support suspended below the base of the instrument. This box may contain a drawer in which the memorandum pad is suitably attached, or, as shown, the bottom 12 of said box may be made movable longitudinally. To this end its longitudinal edges are guided in lateral grooves 10^a of the side walls and are provided at their rear ends with lugs 12^a which in cooperation with lugs 10^b midway of the side walls of the box will form stops limiting the extent of the outward movement of said bottom. Slidably mounted on this bottom is the back 13 of the loose leaf pad preferably made of sheet metal. This back 13 is provided with downwardly projecting guide members 13^a formed by punching or otherwise and which engage longitudinal slots 12^b formed in the bottom 12. Fasted to this back 13 by loose leaf fastening 60 means 14 or the like are a plurality of cards 15 as usual. The back 13 may be provided at its front end with an upstanding wall 13^b formed with a grasp 13^c.

The pad formed by the cards 14 and back 75 13 is so admeasured that when the drawer or bottom 12 of the box is retracted it will be confined in the space below the base B of the instrument. In this position the upstanding wall 13^b of the back 13 will abut close against 80 the front ends of the side walls of the box 10. When the pad is to be used the same is withdrawn until the bottom abuts with its lugs 12^a against the stops 10^b. The pad 13, 15 will 85 extend beyond the front end of the bottom and be supported thereon so that the cards can be freely turned on their loose leaf fasteners 14 from right to left as shown, or otherwise.

The aforescribed construction facilitates 90 the handling of the device while the instrument is in use.

Another mode of construction is shown in Figs. 4 and 5. Here the support 10' is merely a frame suspended by similar arms 11 to 95 those of the box 10 of the first modification. The back 13' of the pad is pivoted to the front end of said support as at 13^c to swing thereon horizontally. When not in use the pad is swung to be concealed between the sup- 100

port 10' and said base B of the instrument.

It is clear that various other modifications may be made without departing from the principle of my invention. I, therefore, do not wish to confine myself to the details shown and described.

What I claim is:

1. In a device of the character described, a support adapted to be attached to the base 10 of a telephone instrument, a withdrawable member on said support, a slidable withdrawable second member guidedly mounted in longitudinal grooves in said first named member and a memorandum pad mounted on said 15 slidable member.
2. In a device of the character described, a support having clamping members adapted to engage around the base of a telephone, an open front drawer movably mounted on said support, a slidable withdrawable member guidedly mounted in longitudinal slots in the bottom of said drawer and adapted to slide out through the front thereof and a 20 memorandum pad mounted on said slidable member.
3. In a device of the character described, a support having clamping members adapted to engage around the base of a telephone, an open front drawer movably mounted on said 25 support, a slidable withdrawable member mounted in said drawer and having downwardly projecting guide members, longitudinal slots in said drawer in which said 30 guide members are adapted to engage for controlling and guiding the movement of said 35 slidable member through the open front of said drawer and a memorandum pad mounted on said slidable members.
4. A device for mounting a telephone index 40 to the base of a telephone instrument comprising a box shaped support open at its top and at its front, clamping means attached to said support for engaging said base, a withdrawable bottom for said support, said bottom being guided in the side walls of said support, lug members formed at the rear of said bottom and adapted to engage lug members on said side walls for limiting the withdrawal 45 of said bottom from said support, a slidable member mounted on said bottom provided with downwardly projecting lug members for engagement in suitable slots formed in said bottom and means for fastening index 50 sheets to said slidable member.

55 In testimony whereof I affix my signature.
DARIO RAPPAPORT.
